(57) **CLAIM**

The ornamental design for a planter, as shown and described above.

DESCRIPTION

FIG. 1 is a top, front, perspective view of a planter showing my new design;

FIG. 2 is a front elevation view thereof, the rear and side elevations being the same;

FIG. 3 is a top plan view thereof;

FIG. 4 is a top, front perspective view showing a second embodiment of my invention;

FIG. 5 is a front elevation view of FIG. 4, the rear and side elevation views being the same;

FIG. 6 is a top plan view thereof;

FIG. 7 is a top, front perspective view of a third embodiment of my invention;

FIG. 8 is a front elevation view of FIG. 7, the rear and side elevation views being the same;

FIG. 9 is a top plan view thereof;

FIG. 10 is a top, front perspective view of a fourth embodiment of my invention;

FIG. 11 is a front elevation view of FIG. 10, the rear and side elevation views being the same; and,

FIG. 12 is a top plan view thereof.

The broken lines in the figures are for environmental purposes and form no part of the claimed invention.
